UNITED STATES PATENT OFFICE.

MORGAN B. SCHILLER AND OLIVER J. HALLER, OF PITTSBURGH, PENNSYLVANIA, AS-
SIGNORS, BY MESNE ASSIGNMENTS, TO AMERICAN TUBULAR ELEVATOR COMPANY,
A CORPORATION OF PENNSYLVANIA.

TOWER.

Application filed March 26, 1924. Serial No. 701,952.

The present invention relates broadly to towers, and more particularly to towers for use with hoisting apparatus, such as elevators.

5 The purpose of the invention is to provide a tower which is particularly adapted to form the shaft of an elevator employed for raising materials during the construction of a building.

10 A preferred embodiment of the invention is shown in the accompanying drawings, in which—

Figure 1 is a perspective view of a tower employed as an elevator shaft;

15 Figure 2 is a view on an enlarged scale of a portion of one side of the tower;

Figure 3 is a detail view of the top portion of the tower;

20 Figure 4 is a detail view showing the connecting means between a corner post of the tower and the base of the tower;

Figure 5 is a sectional plan view on the line V—V of Figure 4;

25 Figure 6 is a detail view illustrating the coupling means at a joint in the tower;

Figure 7 is a detail view illustrating one way of adjustably connecting a girt to a corner post of the tower;

30 Figure 7^a is a view similar to Figure 7 showing a slight modification; and

Figures 8, 9 and 10 are detail views illustrating the manner of connecting the elevator guides to the tower.

Our improved tower is of the collapsible or knock-down type and comprises a base 2, a top 3 and corner posts 4, each made in sections, and the usual diagonal braces 5 and horizontal girts 6.

40 Each corner post is composed of a plurality of connected tubular sections and is secured at its lower end to the base 2 in the manner illustrated in Figures 4 and 5. The base of the tower is preferably formed of four I-beams arranged, as shown, to form a rectangular frame. At each corner of the frame is a hollow casting 7 adapted to receive the lower end of a corner post and having a flange 8 at its lower end resting upon the upper flanges of the two adjacent I-beams of the base frame, the casting being secured to said I-beams by bolts 9. Each hollow casting is provided with an internal shoulder 10 forming a seat for the lower end of a corner post and each post is fastened

in its casting by a bolt 11 extending through the casting and the lower end portion of the post. Thus it will be seen that the hollow castings 7 form coupling members for the sections of the base of the tower, as well as supports for the corner posts of the tower.

55 A preferred manner of coupling two adjacent sections of a corner post is illustrated in Figure 6. A plug or spool 12 is interposed between the adjacent ends of the two sections and is provided at each end with a reduced portion 13 to fit into the bore of a section of the post and a shoulder 14 forming a seat for the end of the section. This plug therefore insures exact alignment of the ends of the two sections of the post. Fitting around the plug and the end portions of the sections of the post is a sleeve 15, the end portions of the sections being secured in the sleeve by fastening bolts 16 extending through the sleeve and said end portions of the sections. The braces 5 and girts 6 are of tubular form with flattened ends and are fastened to the corner posts at the joints thereof by bolts 17 which pass through openings in the flattened ends of the braces and girts in the sleeves 15 and are tapped into the plugs 12.

70 The top of the tower is also preferably constructed of I-beams connected by hollow castings 7 like those at the base of the tower, these castings having the upper end portions of the corner posts fastened therein. At the top and bottom of the tower the flattened ends of the diagonal braces are fastened to the castings 7 by bolts 18, as illustrated in Figure 4.

75 At opposite sides of the tower are guides 19 for the lift of the elevator. These guides are constructed from angles having a T-section and each guide is made in sections of a length corresponding approximately to the length of the sections of the corner posts. The guides are secured to the girts 6 of the tower in the manner shown in Figures 8, 9 and 10. Two U-bolts 20 and a plate 21 are 80 employed at each joint, the plate being interposed between a girt and the abutting ends of two sections of a guide, the U-bolts embracing the girt and having their ends extending through openings in the plate and flanges of the guide sections, nuts 22 being mounted upon the screw threaded ends of the U-bolts, whereby when the nuts are tightened 85

up, the parts are firmly clamped together and the sections of the guide held in perfect alignment by the backing plate 21. The upper and lower ends of the guides may be secured to the base and top of the tower in any appropriate manner, as by bolts 23.

In erecting a building, a tower of this kind may be set up at any convenient point and the lift employed to elevate materials to any desired height. In order to facilitate loading the lift when it is at the bottom of the tower and unloading it when it is at any desired elevation, some of the diagonal braces may be omitted from one side of the tower and girts 24 employed, which may be slid up or down on the corner posts, or removed, as desired. One way of securing these girts to the corner posts is shown in Figure 7. The opposite ends of each such girt are flattened and curved to conform to the curvature of the corner posts, and cooperating curved clamps 25 are removably fastened to such flattened ends by bolts 26. When it is desired to slide a girt 24 up or down, it is only necessary to loosen the nuts on the bolts 26, or the girt may be removed, if desired, by removing the clamps 25.

In Figure 7^a a slightly modified construction is shown in which U-bolts 27 cooperate with the curved flattened ends of the girts 24 to clamp these girts to the corner posts.

The stages or panels of the tower will preferably all be made of the same height, so that the sections of the corner posts and elevator guides may all be made of the same length, as well as the braces and girts, thus simplifying and standardizing the manufac-

ture of the parts and enabling a tower of any desired height to be erected with a minimum number of different elements.

An important advantage of the invention arises from the provision of a tower of the collapsible, portable type which is constructed of a minimum number of different elements and which is particularly adapted for use with hoisting apparatus.

Another advantage of the invention arises from the provision of a tower of this character which is so constructed as to facilitate the loading and unloading of materials at different elevations.

While we have shown and described a preferred embodiment of the invention, it will be understood that changes may be made in the various details of construction without departing from the spirit of the invention or scope of the appended claim.

We claim:

A knockdown elevator tower comprised of sectional corner posts, a base structure in which the corner posts are removably set, connectors uniting the sections between the corner posts, diagonal and horizontal girts on two sides of the tower having their ends bolted to connectors, sectional elevator guides secured to some of the girts on said two sides of the tower, and horizontal girts on another side of the tower clamped to the leg sections thereof between the connectors.

In testimony whereof we have hereunto set our hands.

MORGAN B. SCHILLER.
OLIVER J. HALLER.
